FOREIGN PATENT DOCUMENTS

JP 8244658 9/1996

Primary Examiner — Mark Goodwin(74) *Attorney, Agent, or Firm* — Liell & McNeil**CLAIM**

The ornamental design for a sweeping track shoe for a track-type machine, as shown.

DESCRIPTION

A portion of the disclosure of this patent document contains material to which a claim for copyright is made. The copyright owner has no objection to the facsimile reproduction by anyone of the patent document or the patent disclosure, as it appears in the United States Patent and Trademark Office patent file or records, but reserves all other copyright rights whatsoever.

FIG. 1 is a perspective view of a first embodiment for a sweeping track shoe for a track-type machine showing our new design;

FIG. 2 is a side view thereof; and,

FIG. 3 is a perspective view of a second embodiment for a sweeping track shoe for a track-type machine showing our new design.

All views not shown in the drawings form no part of the claimed design.
